(57) **CLAIM**

The ornamental design for a fuse holder, as shown and described.

DESCRIPTION

FIG. 1 is a front, right perspective view of a fuse holder showing the new design.

FIG. 2 is a rear, left perspective view of the fuse holder of FIG. 1.

FIG. 3 is a front elevation view of the fuse holder of FIG. 1. FIG. 4 is a rear elevation view of the fuse holder of FIG. 1. FIG. 5 is a left side elevation view of the fuse holder of FIG. 1.

FIG. 6 is a right side elevation view of the fuse holder of FIG. 1.

FIG. 7 is a top plan view of the fuse holder of FIG. 1.

FIG. 8 is a bottom plan view of the fuse holder of FIG. 1.

FIG. 9 is a front, right, top perspective view of the fuse holder of FIG. 1.

FIG. 10 is a rear, left, top perspective view of the fuse holder of FIG. 1.

FIG. 11 is a front, right, bottom perspective view of the fuse holder of FIG. 1; and,

FIG. 12 is a rear, left, bottom perspective view of the fuse holder of FIG. 1.

1 Claim, 10 Drawing Sheets
